JACQUES BIGUET, OF LYON, FRANCE, ASSIGNOR TO RADIO CORPORATION OF AMERICA,
OF NEW YORK, N. Y., A CORPORATION OF DELAWARE

THREE ELECTRODE VACUUM TUBE

Application filed August 29, 1921, Serial No. 496,554, and in France October 23, 1915.

This invention relates to improvements in vacuum tubes of the audion type and comprises means for mounting the elements consisting of a plate, grid, and filament comprised in the apparatus, the device being particularly suitable for relays and generators of sustained oscillations of low power. The simple and strong construction of the device adapts it for manufacturing in quantities.

In the annexed drawings, wherein like reference characters are used to designate similar elements, Figures 1 and 2 illustrate two views of the apparatus, taken from two opposite directions.

Figure 3 is a view of the stem with the leads sealed therein;

Figure 4 is a similar view showing the leads in their final shape before mounting the several electrodes;

Figures 5 and 6 illustrate perspective views of different types of plate electrodes that may be used;

Figure 7 shows one form of grid, and

Figure 8 is an alternative form of grid construction.

Into the bulb A is introduced and sealed into the neck of the bulb, in the same way as in the ordinary incandescent lamp, a stem or support B on which are previously fixed or mounted the plate C, grid D and the filament E.

Each of these elements is connected to the pins of the base F by conductors or leads sealed into the stem B.

This stem, represented alone in Figure 3, is formed, as in ordinary lamps, of a flared glass tube with a press into which are sealed the leads *a*, *b*, *c*, *d*, each of which consists of an outside lead *e* of copper, a platinum or equivalent leading-in wire *f*, and an inside lead *g*, preferably of nickel or chrome-nickel.

These leads are during manufacture of the tube given the definite shape illustrated in Figure 4. The plate (Figure 5) is formed of a sheet of metal rolled into cylindrical shape and extended at the middle by one or two hooks *m* and *m'*, each provided with a recess, into which is introduced and pressed the corresponding lead *h*. Another method of con-

struction can also be employed, such as illustrated in Figure 6.

Instead of a solid plate it can be made of a trellis or tissue of tungsten wire as shown in Figure 7.

The coil or grid D illustrated in Figure 8 is composed of a wire of suitable diameter, preferably of tungsten or any other highly refractory metal, rolled helically and having two straight ends which may be clamped or soldered to the ends of a cross bar *h* which is carried by the lead *d*, as indicated in Figure 4.

The rectilinear filament is stretched between the two leads *i* and *j*, shown in the same figure, which may be flattened or lengthened in any manner to give them sufficient elasticity with a view to removing any danger of the filament's breaking.

The three elements of the device being concentrically placed give their maximum effectiveness, especially with regard to the phenomenon of saturation. Moreover, the squat shape of the whole ensures a greater solidity to the apparatus.

When it is employed as generator of maintained waves, the energy expended can be such that the cylindrical plate may be carried to a high temperature; in that case it is advisable to employ a plate of refractory metal such as tungsten. Likewise, the conductors or leads serving as support to the three elements may be of molybdenum or of tungsten; their section may be rectangular instead of being circular, or divided into several wires of minimum section in order to ensure their cooling.

The power of the apparatus may be increased by giving the three elements a greater length, but if the two points of attachment of the coil or grid D are too far away, the latter may give way or be distorted in an injurious manner. In that case it is supported by another and more rigid wire also coiled into a helix but of greater pitch than the grid D and coiled in the opposite direction.

The device illustrated in Figure 9 allows the use of a very fine coil or grid, relatively long and practically undistortable.

What I claim is:

1. A three-electrode vacuum tube having a rectilinear filament, a helical grid surrounding said filament and a cylindrical plate surrounding said grid, a conductor arranged entirely outside of said plate for supporting the grid only at each of its extremities, and a lead-in wire connected to said conductor.
2. A three-electrode vacuum tube having a rectilinear filament, a grid circular-shaped in cross-section and formed of a single continuous wire enclosing said filament, a cylindrical plate surrounding said grid, a conductor arranged entirely outside said plate and parallel to the longitudinal axis thereof for supporting the grid only at each of its extremities, and a lead-in wire connected to said conductor.
3. In an electron-discharge tube, a helical grid electrode, means for supporting said grid electrode comprising a conductor arranged in spaced parallel relation to the axis of the grid electrode and connected to the electrode extremities only, and a lead-in wire joined to said conductor.
4. An electron discharge device comprising a press, concentric grid, filament and plate electrodes supported above said press, a pair of adjacent lead-in conductors for said filament centrally arranged within said press, a lead-in conductor for said grid disposed within said press to one side of said filament lead-in conductors, and a lead-in conductor for said plate disposed within said press to the other side of said filament lead-in conductors and remotely from the grid lead-in conductor, said lead-in conductors forming the sole supporting means for said electrodes.
5. An electron discharge device having a filament, a helical grid surrounding said filament and a cylindrical plate surrounding said grid, a conductor substantially coextensive with and arranged entirely outside of said plate for supporting the grid, and a lead-in wire connected to said conductor.

In testimony whereof I affix my signature.

J. BIGUET.

CERTIFICATE OF CORRECTION.

Patent No. 1,861,107.

May 31, 1932.

JACQUES BIGUET.

It is hereby certified that error appears in the printed specification of the above numbered patent requiring correction as follows: Page 1, lines 54 and 55, strike out the words "as shown in Figure 7", line 56, for the figure "8" read 7 and line 98, for "9" read 8; and that the said Letters Patent should be read with these corrections therein that the same may conform to the record of the case in the Patent Office.

Signed and sealed this 18th day of October, A. D. 1932.

M. J. Moore,

(Seal)

Acting Commissioner of Patents.
